UNITED STATES PATENT OFFICE.

MAX VOIGT, OF NEW YORK, N. Y., ASSIGNOR OF ONE-HALF TO ROBERT G. SCHMIDT, OF SAME PLACE.

LOCK.

SPECIFICATION forming part of Letters Patent No. 295,961, dated April 1, 1884.

Application filed February 2, 1884. (Model.)

To all whom it may concern:

Be it known that I, MAX VOIGT, of New York, in the county and State of New York, have invented a new and Improved Lock for 5 Doors, Drawers, and the like, of which the following is a specification.

Figure 1 is a sectional face view of my improved lock, showing the interior arrangement of the same. Fig. 2 is cross-section of the 10 same, taken on the line *c c*, Fig. 1. Fig. 3 is a face view of the lock. Figs. 4 and 5 are side views, partly in section, of keys that are inserted in said lock. Fig. 6 is a face view, 15 partly in section, of a modified construction of said lock; and Fig. 7, a top view, partly in section, of the same.

This invention relates to door and drawer locks, and has for its object to so construct the lock that if a key fitting it should pass into the 20 hands of unauthorized persons the lock can at once be changed to make that key useless and fitted for an entirely different key.

The invention consists in combining with a lock a movable plate, that has projections for 25 guiding the bit of the key to the tumblers, the set of projections for one key being different from the set for other keys with which the same lock may be opened, all as hereinafter described.

30 The invention also consists in combining with said movable plate means for holding it in any one of several positions, as hereinafter more fully specified.

In Figs. 1 to 5, inclusive, my invention is 35 shown applied to a drawer-lock, or any lock, in fact, which has but one key-hole. In these figures, the letter *A* represents the frame of the lock or its case. *B* is the bolt, and *C* the tumbler, of which a suitable number may be 40 used. *a* is the key-hole, and *D* the key. *b* is the bit of the key.

In the lock-case is shown a pivoted plate, 45 *E*, with notches or apertures *d* at or near its edge, into one of which notches enters a spring-bolt, *e*, of which the handle *f* extends through the side of the lock-case *A*, as in Fig. 3. The axle or pin *g* of the plate *E* also extends through the lock-case, and has a button or handle, *h*, at its outer end, as indicated in 50 Figs. 2, 3, 4, and 5.

On the inner face of the plate *E*, within the lock-case, are series of projections *i*, placed (in this form of lock) radially onto the face of the disk, as shown in Fig. 1. When the key is introduced in this lock through the key-hole *a*, as in Fig. 2, its bit *b* will be in line with one set of projections *i* on the plate *E*, as in Fig. 2, and the key can only be turned so that it may reach the tumblers, and, finally, the bolt *B*, if it can pass the projection *i*, which 55 faces it. In order to do this the said projection *i* must fit the form of the bit, as in Fig. 2. Now, if the key *D*, which is shown in Fig. 2, should be lost or pass into unauthorized hands, or if any danger of such a disposition of the 60 key should exist, the owner of the lock will only have to move the bolt *e* out of the notch of the plate *E*, and then turn said plate *E* so as to bring another of its projections *i* into the path of the key, and then refasten the 65 plate *E* by the bolt *e* in the new position. The new projection thus placed in the path of the key will not enable the first key which was lost to open the lock, but will now require an entirely different key. Thus Fig. 5 shows 70 the plate *E* so turned as to bring the projection *i*, which was lowermost in Fig. 2, to the top into the path of the key. 75

In selling these locks I propose to furnish with each a key or set of keys for every position of the plate *E*. The owner can first use one key or set of keys, and then, when occasion arrives for requiring a change, set the lock so as to render that first key useless, and use the next key or set of keys, and so forth. 80

85 Although I have shown in Fig. 1 the plate *E* to be provided with four such projections *i*, it may be provided with more or less than four such projections, and with a corresponding number of notches or apertures *d*. The button *h*, by which the disk *E* can be turned, may be made detachable, so that the owner can keep it with the spare keys, and affix it to the pivot or axle *g* of the plate *E* only when occasion requires, so that unauthorized persons cannot tamper with the lock. In like manner the button *f* of the bolt *e* may be made detachable. 90 95

When the lock is made with two key-holes, one on each side, for use on an ordinary room door, the plate *E*, instead of carrying the 100

notched projections *i* on its face, will carry them radially on its pivot or axle *g*, as shown in Figs. 6 and 7, the difference between the projections *i* shown in the last-mentioned figures and those shown in Fig. 2 being that for the lock having the two key-holes the projections *i* must have their recesses at the ends, while in the lock having but one key-hole they may have these projections on the face, as appears from a comparison of Figs. 2 and 7; but in every other respect the lock will operate in either case in the same manner.

I claim—

1. In a lock, the combination of its case,

tumblers, and bolt with the movable plate *E*, having series of projections *i* *i*, by which the lock, upon moving said plate, can be fitted for different keys, substantially as specified.

2. The combination of the lock-case *A* with the movable plate *E*, having series of projections *i* for different keys, and having notches or apertures *d*, with the holding-bolt *e*, and means for moving the same, substantially as specified.

MAX VOIGT.
